UNITED STATES PATENT OFFICE

163,280

WHEELBARROW FRAME

John Percy Harrison, London, England, assignor
to Higgs and Hill Limited, London, England, a
body corporate of Great Britain

Application May 11, 1950, Serial No. 9,886
In Great Britain December 16, 1949

Term of patent 14 years

(Cl. D14—3)

To all whom it may concern:

Be it known that I, John Percy Harrison, a subject of the King of England, residing at London, England, have invented a new, original, and ornamental Design for a Wheelbarrow Frame of which the following is a specification, reference being had to the accompanying drawing, forming a part hereof.

Fig. 1 is a perspective view of a wheelbarrow frame, showing the new design;

Fig. 2 is a front elevational view thereof;

Fig. 3 is a top plan view thereof; and

Fig. 4 is a side elevational view of the same.

I claim:

The ornamental design for a wheelbarrow frame, as shown.

JOHN PERCY HARRISON.
